UNITED STATES PATENT OFFICE.

LA VERNE W. NOYES, OF CHICAGO, ILLINOIS.

SHEAF-CARRIER FOR SELF-BINDING HARVESTERS.

SPECIFICATION forming part of Letters Patent No. 392,746, dated November 13, 1888.

Application filed July 23, 1887. Serial No. 245,054. (No model.)

To all whom it may concern:

Be it known that I, LA VERNE W. NOYES, a citizen of the United States, residing at Chicago, in the county of Cook and State of Illinois, have invented certain new and useful Improvements in Sheaf-Carriers for Self-Binding Harvesters, which are fully set forth in the following specification, reference being had to the accompanying drawings, forming part thereof, wherein—

Figure 1 is a rear elevation of part of a self-binding harvester upon which is one of my improved sheaf-carriers. Fig. 2 is an inner or grainward side elevation of part of a harvester including the binder, showing the carrier in the position of dumping. The conveyer and finger-bar are shown in vertical section. Fig. 3 is a detail elevation showing the bundle being forced into the carrier. Fig. 4 is a side, and Fig. 5 is a rear elevation of the carrier-handle and lock. Fig. 6 is a perspective of the sheaf-carrier partly tilted for dumping, the supports of the carrier on the binder-frame and adjacent portion of the sheathing of the binder-deck being shown.

A is the binder-frame.

A' is the breast-plate, which is continued upward from the locality of binding and forms the inner or grainward side of a chute or guide-passage for the bundle from the binder.

A² is the deck, which is likewise continued upward to form the outer or stubbleward side of such passage.

B is the sheaf-carrier frame, which is made of metal tubing bent in U form and pivoted to the frame, the connection being made at one point on each of the parallel arms of the frame B to convenient parts of the frame, the pivot b² at the inner side being set into the horizontal arm A³, and at the outer side the pivot b' being set into the upright arm A⁴. From the outer arm, B', of the carrier-frame are extended upward guard-fingers B⁵, which constitute the outer wall of the carrier, and from the inner arm, B², are extended the fingers B⁶, which reach inward above the binder-frame and deck and at their inner ends curve upward and extend to about the same height as the fingers B⁵ and form both the floor and the inner wall of the sheaf receptacle and carrier. To the outer arm, B', there are also secured the arms B⁸, extending downward a considerable dis-

tance, and have either pivoted to their lower ends or formed integral with them and coiled at that point to make a spring-knee, b³, the arms B⁹, which slant upward across the chute or passage between the deck and the breast-plate to nearly the inner side thereof and nearly the height of the arm B', and are then bent over outward and hooked over the arm B'. 60

To the outer side of the arm B' is pivoted at b⁴ the handle B', which has only slight motion on its pivot between the stops b b. Below its pivot it is curved forward and the end is provided with a notch or shoulder, b⁷, which 65 engages a stud, B¹⁰, on the upright post A⁴.

This carrier is designed to be applied to a binder which discharges the bundle upward, and I have therefore in the drawings shown such a mechanism, being one for which I have 70 made application for patent, filed in the Patent Office the 23d day of July, 1887, Serial No. 245,055. I will not describe this mechanism in detail herein, but only sufficiently to show how it co-operates with the carrier herein 75 shown.

D D are the dischargers, which are hinged to the arms D' D', rotated by the binder-shaft. Said dischargers have the arms D¹, which carry the cam-rolls d², which engage the cams D³, located about the shaft. The form of the cams D³ is such as to hold the dischargers extended while they pass through the locality of binding and upward therefrom between the deck and breast-plate extensions, which bound and 85 form the chute for the upward passage of the bundle, and so that they collapse and withdraw from beneath the bundle after it has been carried to the desired point.

Fig. 1 shows the discharger at its highest 90 operating position just before its cam-roll d² runs off the point of the cam which sustains the discharger in its extended position. As soon as it passes that point the discharger, no longer supported, turns on its pivot on the 95 arm D' and its cam-roll passes into the cut-away part d⁴ of the cam and the discharger is withdrawn longitudinally from underneath the bundle while the arm D' passes over the shaft.

The entire device operates as follows: The bundle is seized by the discharger at its completion and carried around upward between the breast-plate and the deck, and, being pressed

against the trap-gates, which the arms B³ B³⁰ constitute, force said gates outward to the position shown in Fig. 3, the arms B³⁰ either turning on the pivot at the lower end of the 5 arm B³ or the integral structure folding at that point continuing to revolve the dischargers, carry the bundle on upward until the trap-gates, actuated either by gravity or the elasticity of the spring-knee b³, fly back 10 underneath the bundle, resuming the position with respect to the deck and breast-plate from which it was forced by the bundle. The discharger at about this point runs off the cam and is withdrawn longitudinally, as described. 15 The next and each succeeding bundle repeats the process, forcing the preceding bundles over upon the arms or fingers B⁶ until any desired number of bundles up to the full capacity of the receptacle are accumulated. The 20 operator then pressing the handle B⁷ back and down, causes it first to disengage its shoulder b⁷ from the stud B⁷⁰, and then to tip over its pivotal supports on the frame, carrying with it the trap-gates, until it is sufficiently inclined to permit the bundles therein to slide off rearward. This position is shown in Fig. 25 2. Being released by the operator, it returns to its former horizontal position, and is locked securely in that position by the re-engagement 30 of the shoulder b⁷ on the stud B⁷⁰.

I claim—

1. In combination with the self-binding harvester adapted to discharge the sheaves upward, a sheaf-carrier comprising a frame pivoted to the harvester-frame and located higher than the locality of binding, said frame being substantially horizontal in its normal position and having its arms extending grainward above the binder in direction of entering 35 grain, substantially as set forth.

2. In combination with a self-binding harvester having a binder constructed to discharge the sheaves upward, a sheaf-carrier pivoted to the harvester-frame, the trap-gate 40

connected to the carrier-frame and forming a 45 portion of its bottom and moving therewith when the carrier is dumped and adapted to be pushed aside by the sheaf, whereby it permits an entrance to the carrier from beneath, substantially as set forth. 50

3. In combination, substantially as set forth, the upwardly-discharging binder, the carrier-frame B' B², pivoted to a harvester-frame and having the arms B⁶, the trap-gate formed by the arms B³⁰, connected to the frame-arm B', 55 and adapted to be pushed aside by the sheaves, substantially as set forth.

4. In combination with the upwardly-discharging binder, the carrier comprising the frame B' B², having the arms B⁶, the arm B³, 60 extending downward from the said frame, and the trap-gate B³⁰, pivotally connected to the lower end of the arm B', whereby said arms B³⁰ constitute a trap-gate adapted to be pushed aside by the sheaf discharged from 65 binder and to return underneath said sheaf, substantially as set forth.

5. In combination with a self-binding harvester having a binder constructed to discharge the bundles upward, a sheaf-carrier pivoted 70 on the harvester-frame and located above the locality of binding, the axis of its said pivot being transverse to the direction of travel, said carrier comprising a trap-gate in the path of the upward discharge from the binder, constituting the entrance to the carrier from beneath, and a sheaf-receptacle extending back 75 above the binder grainward from the vertical plane of the path of discharge from the binder and entrance to the carrier, and suitable handle to tip the carrier, including its trap-gate, and receptacle to dump it rearward and discharge the sheaves endwise, substantially as set forth.

LA VERNE W. NOYES.
